OSCILLATING DEVICE WITH TWO OSCILLATING MASSES ADAPTED PERIODICALLY TO APPROACH EACH OTHER AND TO REcede FROM EACH OTHER

Wilhelm F. Kluge, Essen, Germany, assignor to Fried. Krupp Stahlbau Rheinhausen, Rheinhausen-Niederrhein, Germany

Application July 27, 1951, Serial No. 238,979

Claims priority, application Germany August 5, 1950

5 Claims. (Cl. 74—87)

The present invention relates to an oscillating device with two oscillating masses periodically approaching each other and receding from each other. More particularly, the invention relates to a device of this type, in which one mass is represented by the working mass, whereas the other mass, acting as counterbalancing mass, is represented by the supporting frame, while driving means are provided in the center of gravity common to the said two masses. According to this invention, the driving means includes unbalanced mass that initiates and sustains oscillation or vibration of the working mass and supporting mass.

According to a known oscillating sifting device of the general type involved, the driving means, and which includes an unbalanced mass, is arranged at the sifting box, or working mass, which latter, by means of inclined connecting rods is journaled in the supporting frame, or counterbalancing mass, so as to be able to oscillate.

It has also been suggested, prior to this invention, to provide yielding power storing means, such as springs or rubber shock absorbers between the said two masses, and by means of the said power storing means to produce counterrunning oscillations.

It is an object of the present invention to improve the heretofore known devices of the type referred to above in order to require only relatively small accelerating forces for actuating the working mass.

It is a further object of this invention to provide an oscillating device with two counter-oscillating masses, i. e., masses which periodically approach each other and recede from each other, in which the mass located at the working frame is as small as possible, while the mass formed by the supporting frame is as heavy as possible.

This distribution of mass between the working frame and the supporting frame is advantageous because the amplitudes of oscillation of the two masses are invariably reciprocal to their weights, the lighter working frame mass thus showing a large, and the heavier supporting frame mass a smaller amplitude; and, the smaller the amplitude of oscillation of the supporting frame, which in turn is yieldably supported by means of springs on the foundation plate, the less are the oscillating forces effecting the foundation of the machine.

It is my discovery that, if an oscillating device is to be driven by means of rotating unbalances the axis of rotation of the driving element must be disposed in the center of gravity of the entire device, i. e. the center of gravity of all masses of the device combined. Only then is it possible to avoid that a lever effect occurs due to the distance between the driving element and the center of gravity of the total mass of the device, which lever effect may lead to rocking or tilting movements of the device.

It is not sufficient to locate the unbalance drive in

2

the center of gravity of the lower mass, i. e. the supporting frame. This known arrangement leads to rocking movements which are particularly undesirable when the device is used as a sieve, because it disturbs considerably the feed of the material to be sifted.

General arrangement

In an effort to keep the mass at the sieve frame as light as possible, while keeping the mass formed by the supporting frame as heavy as possible, the drive for the oscillating masses is, according to the present invention, likewise arranged in the center of gravity of the combined oscillating masses; but in contrast to the heretofore known devices of the type involved, the driving means is arranged at and supported by the supporting frame. Since, thus the rather considerable weight of the driving means is deducted from the mass located at the sieve frame, and, on the other hand, is added to the weight of the supporting frame, the great advantage is obtained that only small accelerating forces are required for driving the working mass (sieve frame), such as the mass effecting the sifting or conveying operation.

Furthermore, with this arrangement, the stresses of the material of this mass are materially reduced when considering the same oscillating amplitude. In conformity with the ratio of the weights of the masses acting against each other, i. e., of the working mass on one hand and the counterbalancing mass represented by the supporting frame on the other hand, an oscillating amplitude for the counterbalancing mass is obtained, which, with the weight distribution mentioned above, is materially less than the oscillating amplitude of the working mass. Consequently, also the accelerating forces for the counterbalancing mass are correspondingly low.

The low weight of the working mass results in a further important advantage. The dimensioning and construction of the power storing means arranged between the two masses is primarily dependent on the weight of the working mass. These power storing means may consist of springs, rubber cushions or rubber shock absorbers. If the working mass is of a relatively greater weight, preferably a series of rubber shock absorbing means is provided.

In many instances, in order to produce pseudo-harmonic oscillations, shock absorbing means are provided, which for the first part of the oscillating movement have a linear spring characteristic, and after a predetermined oscillating amplitude have a nonlinear spring characteristic. The construction of such shock absorbing means becomes simpler the less weight the working mass will have. According to the present invention, rubber shock absorbing means are employed which are so constructed that during the first portion of the oscillating movement, the forces act only on a portion of their cross-section, while only after the shock absorbing means have been compressed to a predetermined extent, the forces act on the entire cross-section of the rubber shock absorbing means.

These and other objects and advantages of the invention will appear more clearly from the following description of the accompanying drawing in which:

Figure 1 diagrammatically illustrates a side view of an oscillating device according to the present invention; and

Figure 2 is a plan view looking down on Figure 1;

Figure 3 is a side view on an enlarged scale of the shock absorbing means used in an oscillating device according to the invention.

Structural arrangement

Referring now to the drawings in detail, the structure shown therein comprises a supporting frame 1 having the center of gravity C, which is yieldably supported

by means of springs 2. Supported by the supporting frame 1 by means of inclined connecting rods or leaf springs 3, is a sifting box 4 having the center of gravity A. On each side of the supporting frame 1 there are arranged two traverses 5 which extend in the oscillating direction of the sifting box, i. e., perpendicular to the connecting means 3. Each of these traverses 5 is provided with a window-like cut-out portion 6.

Arranged inside the cut-out portions 6 at those surfaces thereof which face each other in the oscillating direction of the sifting box 4, are rubber buffers or shock absorbing means 7 and 8. These buffers or shock absorbing means 7 and 8 are arranged in pairs, and each pair at least partly embraces a portion of a cross piece 9 which is connected with the sifting box 4. Since the weight of the sifting box 4 is partially supported by the buffers or shock absorbing means 7, these buffers or shock absorbing means are made correspondingly stronger, while maintaining the desired spring characteristic.

In the center of gravity B of the combined counter oscillating masses there is arranged the driving means 10 mounted in journals 10a on the lower frame 1, which is constructed as the driving means for the device.

This driving means comprises the driven shaft 13 belted or otherwise drivingly connected to drive motor 14. One or more eccentrically positioned masses, at 15, provide for the vibratory movement desired when shaft 13 is driven.

The rubber buffers or shock absorbing means 7 and 8, when viewed in the oscillating direction, have two different effective cross-sections *a* and *b*. When these buffers or shock absorbing means are at rest and also during a predetermined oscillating movement on the device, only the nose-like protruding parts 11 of small cross-section abut the cross piece 9. However, during the remaining part of the oscillating movement, the additional cross-section portions of the buffers or shock absorbing means, i. e., those lateral annular portions 12, which are receding with regard to the central protruding portions 11 having the larger cross section *b*, abut the cross piece 9.

It will be understood that this invention is susceptible to modification in order to adapt it to different usages and conditions, and, accordingly, it is desired to comprehend such modifications within this invention as may fall within the scope of the appended claims.

I claim:

1. In combination in an oscillating device with two counter-oscillating masses, one above the other, one of these masses forming the working mass and the other one representing a frame supporting said working mass and being arranged to oscillate vertically and horizontally, and driving means for causing oscillation of said masses, said driving means, comprising a rotatable shaft and unbalanced mass carried thereby, said driving means being mounted on said supporting frame and located in the center of gravity of the combined masses and on said supporting frame.

2. In combination in an oscillating device with two counter-oscillating masses, one above the other, one of these masses being a working mass and the other one being a frame supporting said working mass and being arranged to oscillate vertically and horizontally, resilient means interposed between said two counterrunning masses and adapted to be compressed by these masses upon relative movement of the masses toward each other, said resilient means having alternate portions of two different cross sections causing two different spring effects successively effective during a complete stroke of the masses toward each other, and driving means comprising a rotatable shaft and unbalanced mass carried thereby for causing oscillation of said masses and located both on said supporting frame and in the center of gravity of the combined masses when stationary.

3. In combination in an oscillating device with two

counter-oscillating masses, one above the other, one of these masses being a working mass and the other one being a frame supporting said working mass and being arranged to oscillate vertically and horizontally, resilient rubber members interposed between said two masses and adapted to be compressed by these masses upon movement of the masses toward each other, each of said resilient rubber members having several portions of at least two different cross-sections arranged to become successively effective during a complete stroke of the masses toward each other, and driving means for causing oscillation of said masses being mounted on said supporting frame and located at the center of gravity of the combined masses when the latter are stationary, said driving means comprising a rotatable shaft and unbalanced mass carried thereby.

4. In combination in an oscillating device, a first oscillating mass formed by a working mass and lying substantially horizontal, a second oscillating mass representing the counterbalancing mass and being also horizontal and spaced beneath the working mass and formed by a supporting frame, means resilient in the vertical direction supporting the frame and flexible in a horizontal plane, rigid link means extending angularly between said masses and pivoted thereto so said first and said second masses when oscillated will periodically approach each other and recede from each other, a plurality of resilient rubber members interposed in distributed relation between said first and said second masses resilient in the direction of relative oscillation of said masses and adapted to be compressed by said oscillating masses, each of said resilient rubber members having portions of at least two different cross-sectional areas distributed therealong in the direction of compression of the member and thus arranged to become successively effective in determining the spring effect of said members during a complete compression stroke, and driving means for causing relative oscillation of said masses said driving means being located in a plane that passes through the individual centers of gravity of said masses and in the center of gravity of the combined masses when at rest, said driving means being mounted on said supporting frame, and comprising a rotatable shaft and unbalanced mass carried thereby, said first and second masses being so arranged that said plane is substantially perpendicular to said link means.

5. In combination in an oscillating device, a first oscillating mass formed by a working mass and lying substantially horizontal, a second oscillating mass representing the counterbalancing mass and being also horizontal and spaced beneath the working mass and formed by a supporting frame, means resilient in the vertical direction supporting the frame and flexible in a horizontal plane, rigid link means extending angularly between said masses and pivoted thereto so said first and said second masses when oscillated will periodically approach each other and recede from each other, a plurality of resilient rubber members interposed in distributed relation between said first and said second masses resilient in the direction of relative oscillation of said masses and adapted to be compressed by said oscillating masses, each of said resilient rubber members having portions of at least two different cross-sectional areas distributed therealong in the direction of compression of the member and thus arranged to become successively effective in determining the spring effect of said members during a complete compression stroke, and driving means for causing relative oscillation of said masses, said driving means being located in a plane that passes through the individual centers of gravity of said masses and in the center of gravity of the combined masses when at rest, said driving means being mounted on said supporting frame, and comprising a rotatable shaft and unbalanced mass carried thereby, said first and second masses being so arranged that said plane is substantially perpendicular to said link means, a stationarily mounted motor for driving said driving means, and means

drivingly connecting said motor with said driving means and extending therebetween in a direction substantially parallel with said link means.
